(57) **CLAIM**

The ornamental design for a hanging apparatus for cookware or bakeware closures or lids, as shown and described.

DESCRIPTION

FIG. 1 is a perspective view of the disclosed hanging apparatus for cookware or bakeware closures or lids; FIG. 2 is a front view of the apparatus of FIG. 1; FIG. 3 is a rear view of the apparatus of FIG. 1; FIG. 4 is a right side view of the apparatus of FIG. 1; FIG. 5 is a left side view of the apparatus of FIG. 1; FIG. 6 is a top view of the apparatus of FIG. 1; FIG. 7 is a bottom view of the apparatus of FIG. 1; and, FIG. 8 is an environmental view of the apparatus of FIG. 1 installed on an exemplary closure or lid of typical cookware/bakeware containers, where the broken lines illustrate the closure or lid and the typical cookware/bakeware containers. Broken lines illustrate environmental features and form no part of the claimed design.
